UNITED STATES PATENT OFFICE.

JOHN T. MEATS, OF TAUNTON, MASSACHUSETTS, ASSIGNOR TO THE MASON MACHINE WORKS, OF SAME PLACE.

LAP DRAWING AND DOUBLING MACHINE.

SPECIFICATION forming part of Letters Patent No. 630,813, dated August 8, 1899.

Application filed January 5, 1899. Serial No. 701,206. (No model.)

To all whom it may concern:

Be it known that I, JOHN T. MEATS, of Taunton, county of Bristol, State of Massachusetts, have invented an Improvement in Lap Drawing and Doubling Machines, of which the following description, in connection with the accompanying drawings, is a specification, like letters on the drawings representing like parts.

This invention has for its object the improvement in machines for drawing and doubling the laps used in the combing of cotton and other fibrous materials; and it comprises means whereby greater automaticity of operation and increased production are secured, together with largely-increased uniformity in the product.

As heretofore made the so-called "ribbon" lap-machine has comprised, essentially, a series of sets of drawing-rolls similar to those used on the ordinary drawing-frame, arranged end to end or in axial alinement, the laps being taken from a plurality of bosses, usually six, each supported between two stands, as on drawing-frames, each set of rolls being arranged to take one lap of the form used on the combing-machine. These laps after having been drawn or attenuated in the usual way and delivered at right angles to the sets of drawing-rolls are each passed over an angle-plate to thereby change the direction of movement of the laps to a path parallel with the axes of the drawing-rolls, in which path the several laps are superposed and conducted to the lap-head of the machine, where they are again formed into a single lap of about the same weight per yard as before being drawn and doubled. After the laps have been drawn in the proportion of about six to one they become very thin and light, hardly thick enough to have the necessary cohesion to reach the lap-head, and it frequently happens that in passing from the angle-plate the lap or web breaks, necessitating the stopping of the machine for the tedious processes of piecing up, a process which cannot possibly be performed without causing an uneven place in the lap, to say nothing of the waste which may be made before the attendant notices the broken web or of the danger of breakage caused by lapping on the front roll, there being no stop-motion controlled from in front

of the drawing-rolls by or through breakage or failure of the drawn lap.

In my present invention the direction of travel of the lap or thin web is not changed after leaving the drawing-rolls, so that the use of the angle-plate is abolished, and I have also provided controlling means for the stop-motion, located at both the back and front of the drawing-rolls, so that in case the web should break or fail either at the back or in front of the rolls the machine will be automatically and instantly stopped.

Figure 1 in side elevation and broken out between its ends represents a lap drawing and doubling machine embodying one form of my invention, the lap-head shown being of usual construction. Fig. 2 is a left-hand end elevation of the machine shown in Fig. 1, the belt-shipper being omitted. Fig. 3 is an enlarged side elevation of the last or right-hand end set of drawing-rolls shown in Fig. 1 to show more clearly the construction of the stop-motion - controlling means and also a portion of the stop-motion not shown clearly in Fig. 1. Fig. 4 is a partial transverse view of the drawing and feed rolls shown in Fig. 3, with the gearing for actuating the same; and Fig. 5 is a partially-diagrammatic view of the gearing shown in Fig. 4.

The main frame comprises an upright end portion A, connected by longitudinal girders or beams A' with the frame L' of the lap-head L, the latter being of usual construction, and upon the main frame I have erected a series of upright stands a along the rear side, connected by a suitable box or other beam a', extended longitudinally of the machine, to form a support for the bearing-rolls of the wound laps B.

Referring to Figs. 1 and 2, arms a² are extended laterally from the beam a' and upturned at their outer ends to form bearings a³ for the journals at the front ends of bearing or lap rolls b, preferably fluted and upon which the lap rests, the journals at the rear ends of said rolls being supported in brackets a⁴, (see Fig. 1,) mounted on the longitudinal support or beam a'.

In my present invention I have arranged the sets of drawing-rolls in tandem on the frame of the machine—that is to say, the sev-

eral sets of drawing-rolls are arranged one behind the other with their axes in parallelism—and usually there will be six sets of rolls forming a complete machine, each set of rolls receiving its lap from the roll B supported above it, and inasmuch as one set of rolls is precisely like another set I shall herein describe but a single set.

Referring now to Figs. 1, 2, and 3, open 10 stands d , arranged in pairs, are mounted on the girders A' , said stands being provided with bearings d' of usual construction for the drawing-rolls d^x , arranged in pairs one above the other, as is common, and I have herein 15 shown four pairs of rolls constituting each set. The rolls of a set are located below the lap-bearing rolls b . The lap t as it leaves the boss is carried around a back stop-roll d^2 , preferably rotatably mounted in rocker- 20 arms d^3 , fulcrumed at their lower ends at d^4 on the stands d , one of said arms, as best shown in Fig. 3, having a shoulder d^5 , normally held by the pull or tension of the lap out of the path of movement of a lug f , fast 25 on a rock-shaft f^x , mounted on the roll-stand and provided with a depending arm f' , pivotally connected to a connecting-rod f^2 , extended continuously below the several sets of drawing-rolls, as shown in Fig. 3, and connected 30 with the rocker-arm f' on the stand of each set. This bar is provided at its forward end with a laterally-projecting pin or stud f^3 , which enters the inclined slot f^4 of a link f^5 , shown best in Fig. 3 as provided at its opposite end with a strap f^6 to embrace an eccentric f^7 , fast on the shaft L^2 of one of the drawing-rolls of the lap-head, so that by rotation of said shaft the link f^5 will be normally reciprocated longitudinally to impart a similar movement to the rod f^2 , and thereby rock the arms f' and their shafts f^x in unison.

Should the lap t fail or break on its way to the back drawing-rolls of a set, the back stop-roll d^2 will be permitted to move into dotted-line position, Fig. 3, bringing the shoulder d^5 into position to engage and stop the lug f of the adjacent rock-shaft, and the reciprocatory movement of the connecting-rod f^2 will also be stopped thereby.

Owing to the inclination of the slot f^4 the link f^5 will be lifted as it is moved in the direction of the arrow 10, Fig. 3, upon such stoppage of the connecting-rod f^2 into dotted-line position, and as it is so raised it will lift a depending rod f^8 , said rod being overturned at its upper end at f^9 to rest on the link f^5 and pivotally connected at its lower end at f^{10} to a dog or detent f^{12} , fulcrumed on the frame at f^{13} . This dog normally enters a notch g' 50 in a shipper-rod g , extended longitudinally of the machine and connected at its opposite end to an arm g^2 , (see Fig. 1,) having attached thereto the belt-fork g^3 , a suitable spring S being attached at one end to the shipper-rod and at its other end to the frame of the machine, said spring normally tending 60 to move the shipper-rod in the direction of

the arrow 12, Figs. 1 and 3. When the link f^5 is lifted, as has been described, the dog or detent f^{12} is disengaged from the shipper-rod, 70 and the latter is moved by its spring S to shift the belt from the fast to the loose pulley to thereby stop the machine.

After the lap has been drawn it passes from the front drawing-rolls without changing its 75 forward direction of movement between suitable feed or calender rolls c and onto a fixed, as herein shown, horizontal support or table T , Fig. 1, upon which it travels to the drawing-rolls of the lap-head, and as the drawn laps 80 are delivered from each set of drawing-rolls they will be superposed one upon the other, so that such "compound" lap, as it may be termed, will pass to the lap-head L .

It is highly important that the stop-motion 85 for the machine be controlled by or through breakage or failure of the drawn lap, and in addition to the controlling means for the stop-motion operated by or through breakage or failure of the lap at the back of the rolls I 90 have provided means, located at the front of the drawing-rolls, to also control the operation of the stop-motion.

Between the front drawing-rolls and the feed or calender rolls c I have interposed a 95 tilting apron h , preferably made of thin sheet metal, fulcrumed at h' on the drawing-roll stand and serving as a guide or support under normal conditions for the drawn lap on its way to the rolls c , said apron having attached thereto at its under side a rearwardly-extended arm h^2 , provided with an adjustable weight w , said arm and its weight tending to tilt the apron into dotted-line position, Fig. 3, such tendency being counteracted by the 100 drawn lap as it passes thereover. The free end of the arm h^2 is arranged above one end of a lever h^3 , fulcrumed at h^4 on the stand, the other and heavier end of said lever being thereby normally retained out of the path of 110 movement of a lug f^{18} on the rock-shaft f^x .

When the drawn lap breaks or fails, the apron h tilts on its fulcrum into dotted-line position and raises the rear end of the lever h^3 into the path of and to stop the rocking 115 movement of the lug f^{18} and its rock-shaft f^x , and, as has been before described, such stoppage will act to effect the operation of the stop-motion, and thereby stop the machine. The upper end, as h^5 , of the apron may be 120 bent over and extended beneath the lower one of the front pair of drawing-rolls, to be depressed by winding of a lap end on the lower roll. Each set of drawing-rolls is provided with such stop-motion-controlling 125 means operated by or through breakage or failure of the drawn lap.

While the tandem arrangement of the sets of drawing-rolls herein shown involves more gearing than in the machines heretofore constructed, such addition is more than overbalanced by the abolition of the very expensive angle-plates for changing the direction of movement of the drawn laps, inasmuch as 130

these plates must in the first place be finished with the greatest nicety and thereafter be kept constantly polished to the highest degree in order to prevent the sticking or breaking of the thin web, a source of much trouble with such machines under certain atmospheric conditions. Furthermore, the delicate operation of changing the direction of movement of so thin a web restricted the speed of the machine to a comparatively low limit, as did also the lack of any form of controlling device for the stop-motion operated by or through the drawn lap.

The frame of the machine is provided with suitable bearings for a main shaft M, having fast and loose pulleys M' M² thereon, Fig. 1, and a pinion m in mesh with a gear m', mounted on the end A of the machine, said gear m' driving by means of an intermediate gear m² a third gear m³, fast on an actuating-shaft m⁴, extended longitudinally of the machine and mounted in suitable bearings on the stands a at the back of the machine. This common actuating-shaft is connected by suitable gearing with and to drive the drawing-rolls of each set and the bearing-rolls b for the lap-roll.

Referring to Fig. 4, the shaft m⁴ has a bevel-pinion m⁴ thereon opposite each set of drawing-rolls and in mesh with a like pinion m⁵ on the extended shaft d⁶ of the lower roll d⁶ of the back pair, and from this shaft by suitable gears M¹⁰, Figs. 4 and 5, of usual construction the several pairs of rolls forming a set are driven, and as such specific gearing forms no part of my invention and is of old and well-known construction in the art I have not deemed it necessary herein to describe it in detail. A sprocket-wheel m⁶ on the last or extreme left-hand shaft d⁶ is connected by a sprocket-wheel m⁸ on a shaft m⁹, supported on the stand a, said shaft m⁹ having fast upon it a pinion m¹⁰, in mesh with a gear b²⁰, (see Fig. 2,) fast on the shaft b²² of one of the bearing-rolls b, to drive the latter positively through an intermediate pinion b²⁴ to rotate a gear b²⁶ on the front bearing-roll of the pair, whereby the lap-roll B will be positively rotated to unwind it.

I prefer to transmit rotation to the several sets of lap supporting or bearing rolls b from the pair driven, as described, and for this purpose the shaft m⁹ has fast upon its rear end a bevel-pinion m¹², in mesh with a like pinion m¹³ on a shaft m¹⁴, extended along the back of the machine and mounted in suitable bearings on the beam a'. Adjacent each of the other pairs of lap-rolls b is a similar intermediate shaft m⁹, provided with a bevel-pinion m¹² to engage a like pinion m¹³ on the shaft m¹⁴, the shaft m⁹ also having a pinion m¹⁰ to drive the gear b²⁰ of it adjacent set of rolls.

I have shown in Figs. 4 and 5 the journal of the lower calender-roll c of each pair as provided with a bevel-pinion c⁵, in mesh with a like pinion c⁶ on a shaft c⁷, extended up-

ward to engage through a bevel-gear c⁸ on its upper end a like gear c⁹ on the shaft of the lower one of the front pair of drawing-rolls 70 d⁶ of the corresponding set.

The stop-motion for the machine, comprising, essentially, the belt-shipper, shipper-rod g, and detent or dog f¹², is controlled as to its operation by or through any of the several 75 laps before the laps are drawn as well as afterward, and this latter is a most important feature and broadly new, so far as I am aware.

The devices intermediate the lap as it enters and leaves the set of drawing-rolls and 80 the stop-motion constitute controlling means for the latter, so that the operation of the stop-motion will be effected by or through an abnormal condition of the lap.

My invention is not restricted to the precise construction and arrangement shown, as the same may be varied or rearranged without departing from the scope or spirit of my invention.

Having described my invention, what I 90 claim as new, and desire to secure by Letters Patent, is—

1. In a lap drawing and doubling machine, a plurality of sets of drawing-rolls arranged in tandem, and means to superpose the drawn 95 laps or thin webs one upon the other without change in their direction of movement and to move them longitudinally in unison.

2. In a lap drawing and doubling machine, a plurality of sets of drawing-rolls arranged 100 in tandem, a common actuating-shaft extended longitudinally of the machine, connections intermediate said shaft and the sets of drawing-rolls, to actuate the latter, and means to superpose the drawn laps one upon another 105 as they leave the drawing-rolls without change in their direction of movement.

3. In a lap drawing and doubling machine, a plurality of sets of drawing-rolls arranged 110 in tandem, a bearing for and arranged to unwind the boss or lap, located above each set of drawing-rolls, means to actuate said bearings, and a support for the drawn laps, over which they travel from the rolls without change in their direction of movement. 115

4. In a lap drawing and doubling machine, a plurality of sets of drawing-rolls, a stop-motion for the machine, and tilting guides for the drawn laps, constituting also members of 120 controlling means for the stop-motion, a guide being located in front of each set of drawing-rolls and operated by or through breakage or failure of a drawn lap to effect actuation of the stop-motion.

5. In a lap drawing and doubling machine, 125 a plurality of sets of drawing-rolls, arranged in tandem, a support for the drawn laps, over which they travel from the drawing-rolls without change in their direction of movement, a stop-motion for the machine, and controlling means therefor located between each 130 set of rolls and said support, operative by or through breakage or failure of a drawn lap to stop the machine.

6. In a lap drawing and doubling machine, a plurality of sets of drawing-rolls arranged in tandem, a stop-motion for the machine, and controlling means therefor adjacent each 5 set of rolls, said means comprising independent members located respectively at the back and in front of the corresponding set of drawing-rolls, to effect the operation of the stop-motion upon breakage or failure of the lap 10 as it enters the drawing-rolls or after it has been drawn.

7. In a lap drawing and doubling machine, a plurality of sets of drawing-rolls arranged in tandem, a stop-motion for the machine, a 15 support below the drawing-rolls and extended in the direction of travel of the drawn

laps, to sustain the latter as they are superposed thereupon, a tilting apron located between the delivery end of each set of rolls and said support, normally acting as a guide 20 for the drawn lap, and connections between said apron and the stop-motion, operative upon breakage or failure of the drawn lap to effect the actuation of the stop-motion.

In testimony whereof I have signed my 25 name to this specification in the presence of two subscribing witnesses.

JOHN T. MEATS.
